UNITED STATES PATENT OFFICE.

ERNEST W. SLICK, OF GARY, INDIANA.

BURGLAR-ALARM.

1,189,009.

Specification of Letters Patent. Patented June 27, 1916.

Application filed September 11, 1915. Serial No. 50,277.

To all whom it may concern:

Be it known that I, ERNEST W. SLICK, a citizen of the United States, residing at Gary, in the county of Lake and State of Indiana, have invented new and useful Improvements in Burglar-Alarms, of which the following is a specification.

This invention relates to certain novel and useful improvements in burglar alarms.

In carrying out the present invention it is my purpose to provide a burglar alarm which may be readily and quickly applied to a door, adjacent to the key hole thereof so that in the event of any one inserting a key into the lock the alarm will be operated to advise the occupants of the protected structure of the attempted entry and which may be applied to windows so that should any one attempt to force such window the alarm will be sounded.

With the above and other objects in view the invention consists in the construction, combination and arrangement of parts hereinafter set forth in and falling within the scope of the claims.

In the accompanying drawings, Figure 1 is a view in side elevation of my improved alarm apparatus the same being shown as applied to a door. Fig. 2 is a view showing my invention applied to a window. Fig. 3 is an end view of the device.

Referring now to the drawing in detail 1 designates a strip of wood or other material while 2 indicates a length of wire coiled upon itself between its ends to form a spring 3 and having one of the legs thereof coiled about the strip 1 as at 4 and then projected upwardly as at 5 and formed to provide a loop 6, and the other leg lying parallel with the upper edge of the strip 1 and formed centrally to provide an impact member 7. The end of the leg of the spring formed with the member 7 remote from the spring 3 terminates adjacent to one end of the strip 1, while the spring 3 is arranged at the other end of the strip. Mounted within the loop 6 and suitably fastened therein is a cork 8 or other holder and formed in the lower side of the cork 8 is a recess 9 adapted to receive the impact member 7. Also formed in the lower end of the cork contiguous to the inner end of the recess 9 is an opening 10 designed to hold the powder cap or other detonating element.

When applying the device to a door one

end of the strip of wood and the adjacent end of the leg of the spring formed with the impact member 7 are arranged in the keyhole as illustrated in Fig. 1, and the end 60 of said leg of the spring engaged with the upper wall of the key hole to hold the leg under tension and against movement under the action of the spring 3. When a key is inserted in the key hole such key forces the 65 particular end of the leg of the wire out of the key hole and as soon as such leg is relieved of the influence of the wall of the key hole the spring 3 re-acts and throws said leg upwardly thereby forcing the member 7 70 through the recess 9 and into engagement with the powder cap 11 with the effect to explode such cap. Thus the occupants of the protected structure are advised of the attempted entry.

When applying the device to a window, cleats 12-12 are employed and fastened to the meeting rails of the respective sash frames of the window, and the ends of the strip 1 and the leg of the wire lying parallel 80 with the strip engaged with the respective cleats so that in the event of attempt being made to force the window open the leg of the wire will be released and the cap detonated as previously described.

While I have herein shown and described one particular form of my invention I wish it to be understood that I do not limit or confine myself to the precise details of construction herein described and delineated 90 as modifications and variations may be made within the scope of the claims and without departing from the spirit of the invention.

I claim:

1. A device of the class described comprising a securing strip, a length of wire coiled upon itself between its ends to form a spring and having one leg wrapped about said strip and then projected upwardly and the remaining leg adapted to be held in proximity to the strip and formed to provide an impact member and a detonating element carried by the upper end of the upwardly projecting portion of the first mentioned leg of said wire and disposed in the path of movement of said impact member, whereby said element may be exploded in the upward movement of the leg formed with said member.

2. A device of the class described comprising a securing strip, a length of wire coiled upon itself between its ends to form

a spring and having one leg wrapped about said strip and then projected upwardly and the remaining leg adapted to be held in proximity to the strip and formed to provide an impact member and the upper end of the upwardly projecting portion of the first mentioned leg of said wire being formed to provide a loop, a holder within said loop and a detonating element carried by said holder and disposed in the path of move-

ment of said impact member whereby said detonating element will be exploded in the upward movement of the leg formed with said member.

In testimony whereof I affix my signature 15
in presence of two witnesses.

ERNEST W. SLICK.
